PRINT BLANKET WASHING APPARATUS

James H. A. S. McMordie, Arlington, and Manson E. Wood, Wakefield, Mass., assignors to Dewey and Almy Chemical Company, North Cambridge, Mass., a corporation of Massachusetts

Application July 26, 1941, Serial No. 404,209

5 Claims. (Cl. 101—423)

This invention relates to textile printing blanket washing apparatus, particularly to apparatus used in textile printing machines operated without back grays.

The objects of the invention are to secure a more thorough and complete cleansing of the blanket; to prevent dried color from building up on the blanket; to provide an apparatus incapable of creasing, tearing or pinching the blanket; and to provide a washing apparatus capable of removing all of the color and as much of the wash water as possible so that the load of water to be evaporated by the dryer may be decreased.

In textile printing, if the use of a back gray is to be eliminated, its function, which is to pick up and carry away the surplus color forced through the printed textile, must be performed by the blanket itself. No-back-gray or "wash" machines, therefore, include a long, endless, waterproof blanket which is washed free of ink and dried before it again is presented at the printing station. As first produced, the blanket had such small ink carrying capacity that the "wash" process was strictly limited to very light patterns. More recently, the surface of the blanket has been modified to give it great ink holding capacity and retentiveness. Blankets now are capable of carrying away all of the color forced through the textile even when blotch patterns are used. None the less, only certain patterns can be printed with complete success; the others still cannot be printed without a back gray, for even if a blanket is able successfully to carry away the surplus ink, the large charge of ink cannot be properly removed by conventional blanket cleansing apparatus.

Color which is left on the blanket turns into a horny mass in the dryer. It does not absorb fresh color, but causes flushing of colors in the design.

Why certain patterns print satisfactorily while others flush depends upon a surprising number of process happenings which, because of the job-to-job nature of the finishing business, vary greatly. For example, the specific textile used, tightness of yarn twist, depth and type of engraving, temperature of the blanket, nature of the dye adhesive—whether British, finishers' gums, etc., are used, and the way each printer handles his color and sets his rolls, all determine the amount and condition of color left on the blanket.

The speeds of textile printing are high—ranging from 40 to 120 yards a minute and averaging about 80 yards; the time interval after the color

has been applied to the blanket and before it reaches the conventional washer is at least 10 seconds; the temperature of the blanket is about 120–130° F. The time and temperature are both great enough to permit a change in the dextrine or other adhesive. These are the reasons why some patterns cannot be printed, for if the dextrine dries to a continuous film, or if there is too much of it, or even if its surface has hardened somewhat, the conventional washer cannot get the color off in the time which the printing speeds permit. Hence, color builds up on the blanket.

Essentially, all bodiers or gums used in textile printing are lyophilic colloids. These have a common property of swelling in water, but the manner of swelling is best illustrated by joiner's flake glue. In water, the surface of the glue becomes slimy at once, but the center remains quite hard for a long time because the swelling of the surface holds back the penetration of water into the interior layers. We have discovered that this happens on the blanket as well and no reasonable amount of water will penetrate the entire layer and no reasonable degree of scrubbing will sufficiently dislodge the color left by the patterns which give trouble in the time which is available if conventional practice is followed.

We divide the washing operation between two stations in the run of the blanket. One, we locate as close as possible to the print cylinders, the other remains in its conventional location at the end of the outward run. As the first step, we pick off by adhesion as much color from the blanket as is possible. Immediately after removing a substantial part of the color mechanically, we scrub the blanket with a wet counter-running brush. We also form a pool or sheet of hot water on the blanket and maintain the sheet over the whole outward run of the blanket until it reaches the second part of the washing mechanism. Because the brush has loosened the soft color and broken it into clots rather than leaving it as a film, and because, afterwards, the color has had at least 10 seconds in which to swell in hot water, the first rubber squeeze roll or "cleaner roll" of the washer squeezes the colored slime off and leaves the blanket practically clean. The blanket then passes over a chisel jet of water which cuts off any remaining surface film and then is squeeze-dried by passing under a second rubber roll and "blotted" by a felt roller. Because only thoroughly broken-up, softened and dilute color reaches this part of the machine, we are able to pay much more attention to the mechanical re-

moval of water at this point and send on to the dryer a blanket which carries a much thinner film of surface moisture.

Referrings to the drawings, Figure 1 shows an elevation of the machine. Details of the printer and dryer are not shown but their respective position is indicated;

Figure 2 is an end view of the "dryer end" washer;

Figure 3 is a section partly in elevation taken 10 on the line 3—3 of Figure 2;

Figure 4 is an end view of the "print end" washer apparatus;

Figure 5 is a central section of the same apparatus;

Figure 6 is a section partly in elevation of the "print end" washer taken on the line 6—6 of Figure 4; and

Figure 7 is a section taken on the line 7—7 of Figure 1.

In Figure 1 the impression cylinder of the textile printing press is indicated at 10. (Color or print rolls are conventional and not shown.) The blanket 11 passes over the impression cylinder 10 and is properly guided by the rolls 12, 12.

In the return run of the blanket 11, but located as closely to the impression cylinder 10 as is practicable yet still avoid interference with the rising web of printed goods, we place a transfer roll 13 against which the wet colored face of the blanket runs. The run of the blanket then continues under the roll 14 and back toward the rear of the machine.

Roll 14 (see Figures 4 and 6) is connected by 35 the sprockets 15 and 16 and by the chain 17 in such a manner that the brush 18 is driven in an opposing direction against the face of the blanket 11. All of the color which can be removed by adhesion to another surface is picked off on the solid face of the roll 13 which also, because of 40 its small diameter aids in breaking up the color mass which clings to the face of the blanket. Roll 13 is continuously cleaned by water fed through the drilled pipe 19 and is scraped clean by the doctor blade 21. The soft color is further broken up and scrubbed by the brush 18 which itself is washed clean by its rotation through the tank 22 of water. It is continuously supplied with fresh water through the drilled pipe 23. Both color scraped off by the doctor blade 21 and the wash water run immediately to waste through the drains 25, 25 (see Figures 4 and 6). The level of water in the tank 22 is controlled by the position of the dam 26. A slide gate 27 allows the water in the tank 22 to be drained when desired.

Enough water is forced through the drilled pipe 23 and into the bite between the brush 18 and the roll 14 not only to wet the brush but to form a continuous sheet of water on the blanket 11 which travels with the blanket throughout the whole length of its rearward run. To prevent the water slopping over the margins of the blanket, the blanket boards 24, 24 (Figures 1 and 7) which support the rearward run of the blanket above the drier are shaped in a shallow V form inclining towards the center to maintain the sheet of water over the whole colored portion of the blanket, but leave the margins dry.

Color is never applied to the full face of a printing blanket. The unsupported margins of a blanket "break away" under the printing roll pressure destroying printability. Consequently, two stripes or bands about two inches wide on the face of the blanket adjacent its margins are color free. It is essential that the brush 18 be narrower than

the blanket 11, and preferably not wider than the spread of color on its face, because the lapping on the cylinder 10 is seldom accurately enough applied to allow the blanket to run without some weaving from side to side. If the brush 18 were allowed to overrun the margins of the blanket 11, color would be forced behind the blanket where it ultimately builds up to cause destructive troubles. The proper relationship of brush and blanket is best illustrated in Figure 6.

The axial position of the brush 18 may be adjusted by means of the adjusting screws 28 and 29 to compensate for bristle wear. The drive chain is adjusted by loosening the stud 31 and 15 sliding the slotted bracket 32 which carries the idler 33 into proper position.

At the rear of the machine the blanket passes over the guide rolls 34, 34 and then drops to loop about the drum 35 of the "dryer end" washer 36 (see Figure 2). Some of the free falling water which is dumped as the blanket enters its vertical run is intercepted by the splash board 37. Most of it with its entrained color may be removed if a squeegee is attached to the splash board and bears against the blanket 11.

25 In that case, fresh water should strike the blanket above the bite and beneath the squeegee, but we find it equally good practice to allow a considerable amount of the falling water to drop into the bite between the blanket and the rubber covered "cleaner" roll 38 where it and the now slimy, swollen, broken-up color paste is squeezed off the blanket and runs down on the inclined deck 39 into the drain sump 41.

Beneath the cleaner roll 38 and as the blanket progresses further around the drum 35, it is met by a stripping spray 40 of water projected from pipe 30. This removes whatever surface film is left on the blanket and the water is then squeezed off as the blanket passes through the bite between the squeegee roll 42 and the drum 35.

Roll 20 is made of felt to act as a "blotter" roll which picks off the free moisture on the face of the blanket 11. It is stripped by a brass doffing 45 roll 43, the purpose of which not only is to squeeze water from the felt and keep it absorptive, but to strip the rings of water which otherwise form beyond the margins of the blanket on roll 20 and so prevent the back of the blanket from getting wet. Removal of free surface moisture and 50 prevention of back wetting reduces to a material degree the evaporation load on the dryer 44.

The type and arrangement of the rolls described above is very satisfactory when dextrine 55 bodied colors are used. With other bodying substances, however, the "print end" washer and rolls alone may not remove all of the color. Whenever this is the case we continue the process of breaking up and mechanically diluting the 60 color begun at the print end washer at the dryer end by replacing roll 38 by a counterdriven brush. Roll 42 also is replaced by a brush, likewise counterdriven, and a second spray cleaner corresponding to spray 40 is arranged to strike 65 the blanket at a symmetrical position on the opposite side of the machine.

When brushes are used, we have found it much more satisfactory to use a brush having bristles made of an artificial fibre, for example the one 70 trade-marked "Nylon," since the extremely smooth surface on these bristles gives no anchorage for the gummy color which the brush removes. Natural bristles generally have not proved as satisfactory as plain rolls.

75 The water which supplies pipes 19, 23 and 30

is furnished by a local pressure pump (not shown). It receives its water from the supply tank 45, which is connected to the mill water supply through the ball cock 46. This is necessary to prevent fluctuations in the mill supply from changing the pumping rate.

The structure of the evaporator dryer forms no part of this invention but, essentially, the blanket travels inwardly in tunnel 41, outwardly in tunnel 48, and in both tunnels is met by a turbulent, hot air blast supplied from the fan house 49.

Every roll in the dryer end washer assembly 36 is brought to bear on the blanket by a spring pressed journal arm, all of which are free save for the tension applied by the springs 50 to rotate about their respective pivots. The compression values of the springs are uniform and are calibrated. The respective roll pressures may be adjusted by setting pointers as shown at 51, 51 opposite marked positions on scales as shown at 52. By carrying every roll on spring pressed journals, no cutting or pinching of the blanket can take place in the washing apparatus.

Textile inks and colors are no longer exclusively confined to vat and developed colors suspended in a water-swelling gum. "Aridye," an emulsion of color particles and a resinous binder is largely used. Water alone is not effective in removing this dye. Consequently, we have used the word water broadly and in the specification and claims intend it shall mean not only water, and water solutions, but any suitable liquid capable of loosening and washing away the color mass.

We claim:

1. In textile printing blanket washing apparatus comprising a textile printer, a washable print blanket, and a dryer for the blanket, blanket washing and color diluting means located adjacent the printing station comprising a color transfer roll, means for removing color from the transfer roll, brushing means capable of scrubbing the blanket surface and means for supplying and maintaining a sheet of water on the outward run of the blanket.

2. In textile printing blanket washing apparatus comprising a textile printer, a washable print blanket, and a dryer for the blanket, means for holding the outward run of the blanket in the form of a shallow trough to retain a sheet of water over the colored portion of the blanket throughout its outward run.

3. The process of removing color from the surface of a textile printing blanket which includes the following steps, mechanically transferring a part of the soft color to a metallic surface, breaking up the film of color adhering to the blanket by wet brushing the film, flooding the remaining color with a swelling agent and diluent, maintaining the diluent in contact with the color and blanket for an appreciable time, and finally removing both diluent and color from the blanket.

4. In textile printing blanket washing apparatus comprising a textile printer, a blanket washer and an endless washable print blanket having a substantially horizontal flight running toward the washer, means located adjacent the printer in advance of said horizontal flight to remove, scrub, break up and dilute the film of color applied to the blanket at the printing station, means to maintain a film of water on the blanket throughout its outward run, and final color removing means located adjacent the end of the outward run of the blanket whereby color softened and diluted by immersion throughout the time required for the outward run is removed from the blanket.

5. In a wash blanket textile printing apparatus a printing cylinder, a printing roll having an engraved printing area, an endless belt-like blanket trained over the printing cylinder and of greater width than the engraved area of the printing roll, blanket cleaning means located adjacent the printing cylinder and including a rotary brush substantially as wide as the engraved area of the printing roll but of less width than the blanket, whereby spreading of excess color beyond the edge of the blanket is avoided.

JAMES H. A. S. McMORDIE.
